UNITED STATES PATENT OFFICE.

JOHN P. BUCHANAN, OF BOSTON, MASSACHUSETTS, ASSIGNOR TO THE HALL SIGNAL COMPANY, OF MAINE.

ELECTRICAL SIGNALING SYSTEM.

SPECIFICATION forming part of Letters Patent No. 596,201, dated December 28, 1897.

Application filed December 27, 1893. Serial No. 494,890. (No model.)

To all whom it may concern:

Be it known that I, JOHN P. BUCHANAN, a citizen of the United States, and a resident of Boston, in the county of Suffolk and State 5 of Massachusetts, have invented a new and useful Improvement in Electrical Signaling Systems, of which the following, taken in connection with the accompanying drawing, is a specification.

10 The invention relates especially to an automatic block system, and has for its main object to decrease the cost of such a system and also to render it less liable to uncertainties of operation consequent upon discharges of 15 lightning or foreign currents.

It consists of the construction hereinafter set forth.

20 The drawing is a diagrammatic view of a portion of a track to which my system is applied, including one complete block and portions of the adjoining blocks.

25 I have shown and prefer to employ in my system rail-circuits for operating the signal-circuits, but of course other forms of track-circuits might in some cases be used in place of the rail-circuits.

30 Referring now to the drawing, A', A², A³, and A⁴ are sections of the track, the sections A' and A² comprising a continuous rail-section 1 and two insulated rail-sections 2 and 3. The track-sections A³ and A⁴ in the same way 35 comprise a continuous rail-section 4 and two insulated rail-sections 5 and 6. The signal B is located near the adjoining ends of the sections A' and A², and the signal B' is located near the adjoining ends of the sections A³ and A⁴. The distance between the signals is one block. B is controlled by a circuit which may be traced as follows: from the signal through 40 the wire r, circuit-controller d, contact-point e, wire f, circuit-controller g, contact-point h, wire a, battery E, wire b, portion of the rail-section 1, and wire c back to signal. Thus it will be seen that the signal-circuit includes a 45 plurality of circuit-controllers and a portion of the rails of the track, but it need not necessarily include any portion of the track, for a separate wire might be substituted for this rail-section. The ends of the rails 1 and 3 are bridged by the wires b and k, which include the battery F. The wire l is connected

5 to the rear end of the rail-section 3 at one end and at its other end to one side of the magnet C. The other side of this magnet is connected to one end of the wire c, the other 55 end of which is connected to the rail-section 1 about midway its ends. The wire m is connected to the forward end of the rail-section 2 and at its other end to the magnet C at a point between the two coils of which the magnet 60 is composed. The rear ends of the rail-sections 1 and 2 are bridged by the wires n and o, which include the magnet M. The circuit for the signal B' is arranged the same way as the circuit for the signal B just described, and the circuits through the rail-sections A³ and A⁴ are arranged in precisely the same way as the circuits through the rail-sections A' and A² just described and include 65 the magnets D and C' similarly arranged. 70

The magnet C' operates the circuit-controller d' in the circuit of the signal B', and the magnet D operates the circuit-controller g in the circuit of the signal B. The magnet C operates the circuit-controller d of the signal 75 B, and the magnet M operates one of the circuit-controllers for the circuit of the signal at the rear of the signal B. Each of the coils of the magnets C and C' is wound to a resistance of four and one-half ohms, and each of the 80 coils of the magnets M and D is wound to a resistance of two ohms. The battery F is the generator for multiple-arc arrangements of the circuits which include the rails of the track-sections A' and A² and the magnets C and M, 85 arranged in the same direction from the battery, and may be traced as follows: from battery F, through wire b, portion of the rail-section 1, wire c, both coils of the magnet C, wire l, and rail-section 3 to battery. This circuit, 90 therefore, since it includes both coils of the magnet C, has a resistance of nine ohms, excluding the resistance of the conductors, and operates the circuit-controller d. The other circuit is from the battery F through wire b, 95 rail-section 1, wire o, magnet M, wire n, rail-section 2, wire m, one coil of the magnet C, wire l, rail-section 3, and wire k to battery. This circuit, therefore, since it includes both coils of the magnet M and one coil of the magnet C, has 100 a resistance of eight and one-half ohms, excluding the resistance of the conductors.

These conductors, however, being of greater length than those of the circuit through one coil of the magnet C, bring the resistance of these two circuits to an approximate balance, 5 so that the current of the battery F is divided, part flowing through both coils of the magnet C and the remaining part flowing through one coil of the magnet C and both coils of the magnet M.

10 The signals are arranged to stand normally at "safety" with all the circuits closed, as shown. The operation is as follows: A train entering upon the rail-section A' shunts in the usual manner the magnet M and drops the circuit controller of the magnet M, breaking the signal-circuit in which it is included and holding its signal at "danger." When the train enters the section A², it shunts both the coils of the magnet C, dropping the circuit-controller 15 d and breaking the circuit for the signal B, which then goes to "danger." As long as any portion of the train remains upon the section A² both the magnets C and M are shunted, and the signal-circuits which they control therefore 20 remain open with their signals at "danger." When the train enters upon the track A³, it shunts the magnet D, maintaining the signal B at "danger" by a second break at the circuit-controller g, and when the train has entirely 25 passed off the section A² the magnets C and M are again energized, the magnet C closing the first break in the signal-circuit, but leaving the signal at "danger" on account of the break at the circuit-controller g and the magnet M, closing the signal-circuit which it 30 controls and putting the signal to "safety." When the train enters upon the section A⁴, it puts the signal B to "danger" by shunting both the coils of the magnet C', still holding 35 the signal B at "danger." As long as the train remains upon the section A⁴ both the magnets C' and D will be shunted, and the circuits which they control will remain open with their signals at "danger." Thus it will be 40 seen that when a train enters a block the signal normally at "safety" is put to "danger" and maintained in this position as long as the train remains in this block or the rear end of the preceding block—viz., the overlap.

45 It will be noted that in my system I have obviated the use of a multiplicity of exposed line-wires, and that the wire f is the only exposed wire that is employed in my system, as shown.

50 Although I prefer to arrange the magnets in the rail-circuits in the manner shown and to wind them to different resistances, as set forth, it is obvious that this is not absolutely essential, the main point being that the arcs 55 of the multiple-arc circuit in which the track-magnets are included should properly apportion the current to the requirements of the magnets. To accomplish this end, resistance-coils might be employed and disposed in the 60 circuit where required, and, moreover, additional battery-power might be used in this multiple-arc circuit instead of depending

upon the common battery F alone; but in no case should the magnets M and D be supplied with battery which cannot be cut out by a 70 train when occupying the sections A² and A⁴, respectively. Various other changes might be made in the system without departing from the spirit of the invention that will occur to any one skilled in the art. For example, the 75 signals could be arranged to stand normally at "danger" instead of at "safety," as by having the magnet C normally unresponsive to its battery and the signal-circuit opening the magnet becoming responsive when the train 80 shunts the magnet M.

Having now described my invention, what I claim as new, and desire to secure by Letters Patent, is—

1. In an electric signaling system the combination of electric conductors arranged in multiple-arc circuits, each of said arc-circuits including an electromagnet and all of said arc-circuits including a common generator, the magnets being arranged in the same direction from said generator along a railway-track, and circuit-controllers operated by said magnets and signaling mechanism operated or controlled by said circuit-controllers, said arc-circuits adapted to be operated in succession 85 by a passing train and so arranged that when a train operates the first arc-circuit the circuit-controller therefor is affected but not the other circuit-controller, and when the train operates the succeeding arc-circuit both circuit-controllers are affected substantially as set forth.

2. In an electric signaling system for railways the combination of a portion of a track, electric conductors which include the rails of the track and arranged in multiple-arc circuits, each of said arc-circuits including an electromagnet and all of said arc-circuits including a common generator, the magnets being arranged in the same direction from said generator, and circuit-controllers operated by said magnets and signaling mechanism operated or controlled by said circuit-controllers, said arc-circuits adapted to be operated in succession by a passing train and so arranged 105 that when a train operates the first arc-circuit the circuit-controller therefor is affected but not the other circuit-controller, and when the train operates the succeeding arc-circuit both circuit-controllers are affected substantially 110 as set forth.

3. In an electric signaling system the combination of electric conductors arranged in multiple-arc circuits, each of said arc-circuits including an electromagnet and all of said 125 arc-circuits including a common generator, the magnets being arranged in the same direction from said generator along a railway-track, and separate signal-circuits operated by said magnets and signaling mechanism 130 operated or controlled by said magnets, said arc-circuits adapted to be operated in succession by a passing train, and so arranged that when a train operates the first arc-circuit the

signal-circuit therefor is affected but not the other signal-circuit, and when the train operates the succeeding arc-circuit both signal-circuits are affected, substantially as set forth.

5 4. In an electric signaling system for rail-ways the combination of a track divided into sections, electric conductors arranged in multiple-arc circuits including the rails of at least two of said track-sections, and another of said 10 arc-circuits including the rails of at least one of said track-sections, each of said arc-circuits also including an electromagnet operating a circuit-controller, substantially as set forth.

5 5. In an electric signaling system for rail-ways the combination of a track divided into sections, electric conductors arranged in multiple-arc circuits including the rails of at least two of said track-sections, and another of said 20 arc-circuits including the rails of at least one of said track-sections, each of said arc-circuits also including an electromagnet operating a circuit-controller, and signal-circuits controlled by said circuit-controllers, substantially as set forth.

25 6. In an electric signaling system the combination of electric conductors arranged in approximately balanced multiple-arc circuits, each of said arc-circuits including an electromagnet and all of said arc-circuits including

30 a common generator, the magnets being ar- ranged in the same direction from said gen- erator along a railway-track, and separate normally-closed signal-circuits operated by said circuit-controllers, said arc-circuits 35 adapted to be operated in succession by a passing train and so arranged that when a train operates the first arc-circuit the circuit-controller therefor is affected but not the other circuit-controller, and when the train oper- ates the succeeding arc-circuit both circuit- 40 controllers are affected, substantially as set forth.

7. In an electric signaling system for rail-ways the combination of a track divided into 45 sections, electric conductors arranged in ap- proximately-balanced multiple-arc circuits, one of said arc-circuits including the rails of at least two of said track-sections, and an- other of said arc-circuits including the rails 50 of at least one of said track-sections, each of said arc-circuits also including an electro- magnet operating a circuit-controller, and a normally-closed signal-circuit controlled by each of said circuit-controllers, substantially 55 as set forth.

8. In an electric signaling system for rail-

ways the combination of two adjoining por- tions of a track, each comprising a long con- tinuous rail-section and two short correspond- ing insulated rail-sections, a rail-circuit in- 60 cluding an electromagnet and one of said short rail-sections and a corresponding por- tion of the long rail-section of one of said por- tions of the track, a second rail-circuit in- cluding an electromagnet, a long rail-section 65 and both of the corresponding short rail-sec- tions of the other portion of the track, and a signal-circuit operated by said magnets, sub- stantially as set forth.

9. In an electric signaling system, the com- 70 bination of a number of multiple-arc circuits, each of which includes the rails of a track, a battery, and a magnet in each of its arc branches, the magnets of a multiple-arc cir- cuit being arranged in the same direction from 75 their common battery and adapted to be suc- cessively short-circuited by a passing train, a series of signaling-circuits including a plu- rality of circuit-controllers, one circuit-con- troller of each signal-circuit being operated 80 by a magnet of a multiple-arc circuit, and another circuit-controller of each signal-cir- cuit being operated by a magnet of a sepa- rate multiple-arc circuit, substantially as set forth. 85

10. In an electric signaling system, the com- bination of a signaling-circuit including a plu- rality of circuit-controllers, two multiple-arc circuits, each of which includes separate 90 insulated sections of track, a battery and a magnet in each of its arc branches, the mag- nets of a multiple-arc circuit being arranged in the same direction from their common bat- tery and adapted to be successively short- 95 circuited by a passing train, one of the mag- nets of each multiple-arc circuit operating a circuit-controller of the signaling-circuit, sub- stantially as set forth.

11. A block-signal system having a track- circuit extending along it and having a gen- 100 erator at one end of the block and being pro- vided with a plurality of relays located at different distances from the generator and adapted to be successively short-circuited through a passing train and signaling mech- 105 anism having circuits controlled by the said relays.
